SCRAPER ASSEMBLY

Earl B. Maloon, Milwaukee, Wis., assignor to The
Heil Co., Milwaukee, Wis., a corporation of
Wisconsin

Application October 2, 1935, Serial No. 43,137

14 Claims. (Cl. 37—124)

The present invention relates in general to improvements in the art of excavating and conveying dirt, gravel and rock, and relates more specifically to improvements in the construction and 5 operation of scrapers for digging and carrying earth and stone in connection with excavating and grading projects.

Generally defined, an object of the present invention is to provide an improved scraper assembly of extremely durable construction having 10 maximum capacity and efficiency.

It has heretofore been proposed to provide a scraper having a main bowl swingably supported upon a rear axle and extending forwardly therefrom; a single central beam or frame swingably supported upon a front axle and extending rearwardly over the bowl, the front portion of the bowl being pivotally attached to the medial portion of the beam frame and the rear portions of the bowl and frame being relatively movable to raise or lower the cutting edge; a rear apron movable within the bowl to discharge the contents; and a front apron pivotally suspended from the frame and movable relative to the forward end of the bowl. Such an assemblage is shown in Patent No. 1,958,195, granted May 8, 1934, to C. LeBleu, and while scrapers embodying the general combination of elements recited, have been quite successful in actual commercial use, 15 these prior devices were undesirably bulky and cumbersome, and lacked sufficient strength to withstand extremely severe service. The use of a single central beam frame in these prior scraper assemblages, produces a relatively high and rather 20 weak support for the carrier bowl, and prevents maximum loading. In these prior structures, the bowl and front apron are also supported from the beam frame by independent and separated pivots, and this suspension makes it impossible 25 to secure most effective coaction between the bowl and apron at all times. Then too, the actuating mechanism for the bowl and aprons of these prior scrapers, were relatively complicated and inefficient, thus making it impossible to 30 handle maximum quantities of material under extremely severe conditions of operation.

It is therefore a more specific object of the present invention to provide various improvements especially applicable to scrapers of the above described type, which will obviate the difficulties and objections referred to.

Another specific object of the invention is to provide an improved bowl supporting and actuating frame which is very durable in construction.

tion, and which does not in any way interfere with maximum loading of the carrier bowl.

A further specific object of the invention is to provide an improved mounting for the bowl and front apron of such scrapers, whereby most effective cooperation between these elements is maintained at all times, and the apron will function to remove the hills of earth and stones from in front of the scraper blade when the bowl is elevated to carrying position.

Still another specific object of the invention is to provide improvements in the hydraulic jacks for actuating the scraper bowl and aprons, whereby these parts may be quickly and positively manipulated at high speed irrespective of the 10 conditions to which the scraper is subjected at the time of actuation of the jacks.

Another specific object of my present invention is to provide improved instrumentalities for facilitating attachment of large scrapers or the like, to a propelling vehicle such as a tractor.

An additional specific object of the invention is to provide a new and useful scraper assemblage which is compact and attractive in appearance, and which may be operated most economically.

These and other objects and advantages will be apparent from the following detailed description.

A clear conception of embodiments of the several features constituting the present invention, and of the mode of constructing and of utilizing scraper assemblages built in accordance therewith, may be had by referring to the drawings accompanying and forming a part of this specification in which like reference characters designate the same or similar parts in the various views.

Fig. 1 is a part sectional side elevation of one of the improved scraper assemblages, showing the main bowl in digging position and the aprons retracted to permit unobstructed digging;

Fig. 2 is a full side elevation of the scraper showing the bowl and aprons in load carrying position;

Fig. 3 is another part sectional side elevation of the assemblage showing the bowl and front apron elevated, and the rear apron moved forwardly to unloading position;

Fig. 4 is a full top view of the scraper unit with the parts positioned as in Fig. 2;

Fig. 5 is an enlarged fragmentary sectional view of the cooperating lower portions of the bowl and front apron, showing the latter in the act of closing and of removing the hill of material in advance of the cutting edge of the bowl; and

Fig. 6 is a similarly enlarged fragmentary sectional view of the front support for the scraper assemblage.

While the invention has been shown and described herein as being specifically applied in a road scraper or grader unit having a main bowl and aprons operable hydraulically and in a particular manner, it is not intended to unnecessarily restrict the scope by such specific embodiment, since some of the novel features are obviously more generally applicable.

Referring to the drawings, the improved scraper assembly comprises in general a main receptacle or bowl 8 supported to swing about a rear pivot or axle 9; a frame 10 supported to swing about a front pivot or fulcrum ball 11 and having rearwardly extending opposite side arms 12 extending along the opposite sides of the bowl 8; aligned pivots 13 connecting the opposite side walls 14 of the bowl 8 with medial portions of the arms 12; a front bucket or apron 15 swingably suspended from the pivots 13 and cooperable with the forward cutting edge 16 of the bowl 8; a rear pusher or apron 17 swingably suspended from the bowl 8 by aligned side pivots 18 and movable along the bowl bottom 19 between the side walls 14; a plurality of hydraulic jacks for independently actuating the bowl 8 and the aprons 15, 17; and power means for operating the jacks.

The main bowl 8 is preferably formed of heavy steel plates welded together, and has rearwardly extending heavy integral brackets 20 which are fulcrumed upon the rear axle 9; and the upper rear portions of the side walls 14 are rigidly interconnected by a beam 21. The cutting or scraping edge 16 is formed upon a removable and reversible plate, and chisel teeth 22 may be removably attached to the cutting edge 16 at spaced intervals as shown in Fig. 4. The frame 10 may also be formed of heavy steel plate or of cast metal, and the side arms 12 are rigidly connected to the opposite ends of a hollow cylindrical cross-beam 23, the medial portion of which is likewise connected to the front goose-neck which carries the pivot ball 11. The bowl 8 and frame 10 may also be additionally reenforced and strengthened wherever desirable in order to produce an extremely durable assemblage capable of withstanding severe stresses without distortion thereof.

The rear ends of the side arms 12 of the frame 10 are rigidly interconnected by a tubular element 24 having rearwardly projecting sets of integral ears 25 disposed closely adjacent to the arm ends, and the cross-beam 21 of the bowl 8 has similar sets of integral ears 43 projecting rearwardly therefrom. Two similar hydraulic jacks each comprising a cylinder 26 pivotally suspended from the adjacent set of ears 27 by trunnions 27', and a piston movable within the cylinder 26 and having a rod 28 pivotally attached to the corresponding set of ears 25 by a pivot pin 29 cooperate with the bowl 8 and frame 10 to relatively swing the same about the aligned pivots 13 which connect the opposite side walls 14 of the bowl with the medial portions of the frame arms 12. These similar jacks have cylinders 26 of like capacity and are simultaneously operable at all times, being disposed substantially vertical and closely adjacent to the rear end of the bowl 8.

The front bucket or apron 15 may likewise be formed of heavy steel plate and comprises a curved forward wall having a substantially tangent lower portion 30 provided with a cutting

edge 31, and side plates 32 provided with rear extensions 33 which are slidable along the inner surfaces of the bowl walls 14 during swinging of the apron 15 about the aligned pivots 13. The mounting of this front apron 15 upon the side pivots 13, avoids obstruction to loading above the bowl and apron; and by utilizing the same pivots 13 which interconnect the bowl 8 and frame 10 to also swingably support the apron 15, the cutting edge 31 will most effectively cooperate with the teeth 22 and edge 16 of the bowl during closing movement of the apron 15 and the tangent apron portion 30 is made most effective in removing hills of material 34 when the bowl 8 is withdrawn from cutting position, see Fig. 5. The outer sides of the apron side plates 32 have brackets 35 which are pivotally attached to the forward ends of side links 36, and these links extend along the side walls 14 of the bowl 8 and have their rear ends pivotally attached to the upper swinging ends of side levers 37 which are mounted upon a rear pivot shaft 38.

The rear pivot shaft 38 is journaled in bearings 39 secured to the lower rear portion of the main bowl 8, and extends entirely across the machine, and this shaft also carries a lever arm 40 at its medial portion between one of the cylinders 26 and the adjacent bowl bracket 20. A second hydraulic jack mechanism comprising a cylinder 41 pivotally suspended by trunnions 42 from ears 43 carried by the rear upper portion of the bowl 8, and a piston having a movable rod 44 pivotally attached to the swinging end of the lever arm 40, is adapted to swing the front apron 15 about the pivots 13 through the arm 40, shaft 38, levers 37 and links 36, independently of the adjusting movement of the main bowl 8.

The rear pusher or apron 17 may also be formed of heavy steel plate, and has opposite side plates 45 which are movable along the inner sides of the bowl walls 14 during swinging of this apron about the pivots 18. The lower edge of the rear apron 17 is adapted to travel closely adjacent to the bowl bottom 19, and the suspension pivots 18 coat with upward extensions 46 secured to the opposite side walls 14 of the main bowl, thereby again avoiding obstruction above the bowl 8 and leaving the top of the bowl open for loading at all times. The rear apron 17 is swingable back and forth within the main bowl, by means of a third hydraulic jack mechanism comprising a cylinder 47 pivotally suspended on trunnions 48 between the spaced brackets 20, and having therein a piston provided with a movable rod 49 which is pivotally connected to a cross-shaft 50 carried by the rear of the apron 17, as clearly shown in Figs. 1, 3 and 4.

The hydraulic jack mechanism for independently actuating the bowl 8, front apron 15, and rear apron 17, are of the double acting type, and are operable by oil circulated by a pump 51, and the flow of which is controllable by valve mechanism 52 carried upon the brackets 20 near an operator's platform 53. The pump 51 may be driven by a motor 54 of any suitable type, and is of sufficient capacity to insure rapid and effective actuation of any or all of the hydraulic jacks at all times. The rear axle 9 which provides a fulcrum support for the bowl brackets 20, is supported from the ground by rear wheels 55, and the fulcrum ball 11 may be likewise supported by front wheels 56 rotatably associated with a draw-bar frame 57. Because of the relatively great weight of the rear scraper assembly, the ball 11 is preferably caused to coact with a socket 58 75

carried by the draft frame 57 and disposed rearwardly of the axis of the wheels 56, as clearly disclosed in Fig. 6. This assemblage facilitates manipulation of the draw bar 59 and attachment thereof to the pulling vehicle.

During normal digging operation of the improved scraper assembly, the device is being transported along the ground by a tractor attached to the draw bar 59, and the bowl 8 and aprons 15, 17 are positioned as shown in Fig. 1. The teeth 22 and cutting edge 16 are being forced through the earth 34 and as the forwardly extending teeth 22 initially pry and loosen the material, the cutting edge 16 approaches the loosened substances whereupon the mixture of earth, stones, and sod is elevated and deposited within the bowl 8. This loading action may be continued until the bowl 8 is filled to overflowing and even after the forward portion of the charge has extended itself forwardly beyond vertical position. The front apron 15 may then be lowered by the operator, as indicated in Fig. 5, and the main bowl 8 may be simultaneously elevated, thus causing the apron portion 30 and cutting edge 31 to approach the teeth 22 and bowl edge 16 and to remove the hill of material 34 which tends to form in front of the bowl 8 during raising thereof. As the front apron 15 engages the teeth 22, the forward portion of the charge drops into the apron 15 and becomes positively confined within the receptacle formed by the bowl 8 and front apron.

When the bowl 8 has been fully raised and the front apron 15 has been lowered to its extreme limit, as illustrated in Fig. 2, the scraper assembly is in carrying or transporting condition. The material may then be transported to any desired location and may be subsequently discharged by the operator upon placing the elements in the position shown in Fig. 3. During unloading, the front apron 15 may be elevated and the rear apron 17 may be brought forwardly as illustrated in Fig. 3, these operations either being successive or simultaneous. Upon elevation of the front apron 15, the forward portion of the charge will drop out of the apron by gravity, and as the pusher apron 17 is moved forwardly, the material forming within the bowl 8 and normally resting upon the bottom thereof, will be positively ejected over the cutting edge 16 and teeth 22 and will drop upon the ground. After the charge has been completely removed, the rear apron 17 may again be returned to a position in substantial contact with the beam 21, and the bowl 8 may again be lowered into digging position.

From the foregoing description it will be apparent that the machine may be quickly and readily manipulated by an operator positioned either upon the platform 53 or upon the tractor, the latter operation being effected through remote controls. The hydraulic jack mechanisms which are operable independently of each other to actuate either the bowl, front apron 15, or rear apron 17, act quickly and positively to actuate these various elements, and the disposition of these jack mechanisms as shown, provides a simple and compact arrangement, and the mechanisms are effectively protected against possible damage. By maintaining the upper portion of the bowl 8 and front apron 15 entirely free from obstruction, the carrier bracket may be loaded to overflowing without danger of damaging any portion of the machine, and without obstruction to the loading. This elimination of obstructions is

due largely to the formation of the frame 10 and to the location of the pivots 13, 18. The suspension of the front apron 15 upon the same pivotal axis as that connecting the bowl 8 and the main frame 10, insures most efficient operation of this apron and coaction thereof with the bowl 8 at all times, and this common suspension and the peculiar formation of the apron 15 also insures effective removal of the hills in front of the main bowl during raising thereof. The entire structure is moreover extremely durable in construction, and the disposition of the pivot socket 58 rearwardly of the axis of rotation of the wheels 56, facilitates manipulation of the draw bar 59 in spite of the fact that the frame 10 and bowl 8 are of relatively heavy construction. The improved scraper has proven highly successful in actual commercial use, and has thoroughly demonstrated its ability to handle large quantities of various kinds of material at a minimum cost per cubic unit.

It should be understood that it is not desired to limit the invention to the exact details of construction and to the precise mode of operation herein shown and described, for various modifications within the scope of the claims may occur to persons skilled in the art.

I claim:—

1. In a scraper, a bowl supported to swing about a rear pivot, a frame supported to swing about a front pivot and having side arms pivotally supporting the front of said bowl outwardly beyond the opposite sides thereof to leave the space above the bowl entirely free from obstruction, means coacting with the rear ends of said arms for relatively moving said bowl and frame to raise and lower said bowl, and an apron cooperable with the front of said bowl and pivotally suspended from said arms to swing about the same pivotal axis about which said bowl is movable relative to said frame.

2. In a scraper, a bowl having a rear fulcrum, a frame having a front fulcrum and spaced arms extending rearwardly along the opposite sides of said bowl to leave the space above the bowl entirely free from obstruction, a pivotal connection between the front of said bowl and a medial portion of each of said frame arms, means coacting with the rear ends of said arms for relatively moving said bowl and frame to move said bowl from digging to carrying position and vice versa, and an apron suspended from said pivotal connection to move toward and away from the front of said bowl.

3. In a scraper, a bowl having a rear supporting axle, a frame having a front pivotal support and side arms extending rearwardly at the opposite sides of said bowl, aligned pivots connecting the opposite sides of said bowl with medial portions of said arms, and a hydraulic jack interposed between the rear end of each of said arms and said bowl for raising and lowering the latter.

4. In a scraper, rear and front wheels, a bowl fulcrumed to swing about said rear wheels, a frame having spaced arms fulcrumed to swing about said front wheels, a pivot connecting a front portion of said bowl with said frame arms, a cross-beam rigidly interconnecting the rear ends of said arms, mechanism coacting directly with said beam for relatively moving said bowl and frame about said pivot, and an apron suspended from said pivot and swingable toward and away from said bowl, the space above said bowl and apron being entirely free from obstruction.

5. In a scraper, a bowl tiltable about a rear pivot, a frame tiltable about a front pivot and having spaced side arms extending along the opposite sides of said bowl, a pivotal connection between each of said side arms and said bowl, an apron swingable about said pivotal connection toward and away from the front of said bowl, and means coacting with the rear ends of said arms for relatively moving said bowl and frame about said pivotal connection.

10 6. In a scraper, a bowl having a front cutting edge and a rear pivotal support, a frame having a front pivotal support and spaced arms extending adjacent to the opposite sides of said bowl, pivot means connecting each side of said bowl with the adjacent frame arm, and means interposed between the rear ends of said arms and said bowl for moving the latter.

15 7. In a scraper, a bowl having a front cutting edge and a rear pivotal support, a frame having a front universal pivotal support and rearwardly extending laterally spaced arms, pivot means connecting the forward side portions of said bowl with the medial portions of said arms, a beam connecting the rear portions of said arms, and jack means interposed between the rear portion of said bowl and said beam.

20 8. In a scraper, a bowl having a curved bottom provided with a front cutting edge and side walls extending upwardly from said bottom and connected at their upper rear ends by a cross-beam, an actuating frame for said bowl having a central front goose-neck and side arms extending rearwardly along the side walls of said bowl, said side walls having their front ends pivotally attached to said beam arms, and elongatable means interposed between the rear ends of said frame arms and the rear bottom portion of said bowl.

25 9. In a scraper, a bowl having a front cutting edge and a pivotal support disposed rearwardly of said edge, a frame having a front pivotal support and spaced side arms extending rearwardly along said bowl, aligned laterally spaced pivots connecting the forward portion of said bowl with the medial portions of said arms, a beam connecting the rear portions of said arms, and laterally spaced hydraulic jacks interposed between said beam and said bowl.

30 10. In a scraper, a bowl having a front cutting edge and side walls, a frame having side arms disposed near the upper portions of said side walls, aligned pivots connecting said arms and

the upper foremost portions of said walls, means associated with the rear ends of said arms for relatively moving said bowl and arms about said pivots, and an apron suspended upon said pivots and movable toward and away from said bowl edge entirely beyond the front ends of said walls, said apron having rear extensions slidably co-operable with said side walls and the space above said bowl and apron being entirely free from obstruction.

10 11. In a scraper, a rearwardly supported bowl, a forwardly supported frame having side arm members extending along the opposite sides of said bowl, aligned pivots connecting the opposite sides of said bowl with said arms, an apron suspended from said pivots and movable toward and away from said bowl, and means associated with rear portions of said arms for relatively moving said frame and bowl to raise and lower the latter, the space above said bowl and apron being entirely free from obstruction.

15 12. In a scraper, a frame having a front pivotal support and integral side arms, a bowl disposed between said side arms, aligned pivots connecting the opposite sides of said bowl with said arms, an apron suspended from said pivots between said arms and movable toward and away from said bowl, and means associated with said arms rearwardly of said pivots for moving said frame to raise and lower said bowl and apron, the space above said bowl and apron being entirely free from obstruction.

20 13. In a scraper, a frame having a front fulcrum and spaced parallel side arms, a bowl disposed between said side arms, pivotal means connecting said bowl with medial portions of said arms, an apron swingably suspended from said arms by said pivotal means and movable toward and away from said bowl, and means coacting with end portions of said arms for raising and lowering said bowl and apron.

25 14. In a scraper, a tiltable frame having rigid side arms, a bowl suspended between said arms, pivots connecting said bowl with said arms, an apron suspended from said pivots for movement toward and away from said bowl, and means associated with said arms rearwardly of said pivots for moving said arms to simultaneously raise or lower said bowl and apron, the space between said arms and above said bowl and apron being entirely free from obstruction.

30 EARL B. MALOON.
